UNITED STATES PATENT OFFICE.

ISAAC N. LEWIS, OF MONTCLAIR, NEW JERSEY.

FIREARM.

Application filed November 23, 1918. Serial No. 263,824.

To all whom it may concern:

Be it known that I, ISAAC NEWTON LEWIS, a citizen of the United States of America, residing at 1 Russell Terrace, Montclair, in 5 the county of Essex and State of New Jersey, have invented certain new and useful Improvements in Firearms, of which the following is a specification.

This invention relates to firearms, and particularly to automatic or semi-automatic firearms in which the gases of discharge resulting from the firing of a powder charge are employed for the purpose of causing operation of the actuating mechanism of the fire- 15 arm.

The primary object of the present invention is to provide an automatic or semi-automatic firearm of extremely simple and light construction and arrangement, involving a 20 minimum number of parts, and which shall be capable of more rapid, efficient and cleaner operation than gas operated firearms as now in use. Another object of the invention is to provide an automatic or semi-automatic 25 firearm constructed and arranged to be operated in accordance with the method of operation described and claimed in my co-pending application No. 263823 filed November 23rd 1918. Other objects are to provide an 30 improved form of firearm in which the gases of discharge are utilized to effect an air cooling of the barrel, and if desired, of the actuating mechanism of the firearm and to provide a firearm in which the gases of dis- 35 charge are utilized in an improved manner to reduce or neutralize the recoil of the fire- arm following the explosion of the powder charge.

The invention primarily consists in an 40 automatic or semi-automatic firearm in which means are provided for influencing the gases of discharge resulting from the firing of a powder charge to produce a shock or very rapid pressure impulse, together 45 with means for transmitting said shock or impulse to the actuating mechanism of the firearm to operate the same.

The shocks or pressure impulses may be produced by providing means for checking 50 or retarding the forward movement of the discharge gases. Such forward movement of the gases is extremely rapid, and the sudden shock or rapid pressure impulse is produced when the movement is momentarily 55 checked or retarded by the contact of the gases with said means. The shocks or im-

pulses may also be produced by providing means for checking or retarding the free expansion of the discharge gases issuing from the muzzle end of the gun barrel. 60

An important distinction must be drawn at the outset between the present automatic or semi-automatic firearm operated by shocks or pressure impulses, and firearms operated by the direct pressure of the heated 65 gases of discharge upon parts connected with the actuating mechanism of the firearm. In the improved firearm the hot gases of discharge do not necessarily come into direct contact with the actuating mechanism or 70 parts connected thereto to transmit the shocks or impulses, as such shocks or impulses may be, and preferably are transmitted to said mechanism, or said parts, through the medium of an intervening column 75 of air. Thus said mechanism, or said parts, do not become highly heated by the gases and do not become fouled by deposits therefrom, enabling the firearm to be operated for more extended periods without 80 cleaning, and preventing jamming or inefficient operation due to said fouling deposits. Furthermore, as the shock or impulse is produced and transmitted to the actuating mechanism practically instantaneously with the discharge of the bullet from 85 the barrel, the speed of operation is increased when firing entirely automatically, and a greater number of bullets may be discharged in any given interval. 90

The invention also consists in an automatic or semi-automatic firearm in which means are provided for influencing the gases of discharge resulting from the firing of a powder charge to produce a shock or very 95 rapid pressure impulse, together with means operated by said shock or impulse to effect a circulation of cooling air over or around the barrel, and if desired, over the actuating mechanism of the gun. 100

The invention further consists in an automatic or semi-automatic firearm, in which means are provided for influencing the gases of discharge resulting from the firing of a powder charge to produce a shock or very 105 rapid pressure impulse of such a nature as to reduce or neutralize the recoil of the firearm due to the explosion of the powder charge.

Still further features of the invention relate to improved constructions and arrangements of the actuating mechanism, trigger 110

mechanism and cartridge magazine of the firearm, in combination with the improved shock operated means above referred to. Another feature relates to the provision of a firing mount in the form of a shield, or body protector adapted to afford protection to a machine gunner when firing the firearm or when advancing under fire. These and other features will be fully described hereinafter and clearly pointed out in the appended claims.

In the accompanying drawings, for the purpose of illustration only, and without any intention of limiting the invention to any particular construction or type of firearm, is shown a machine or rapid fire gun adapted to be operated automatically or semi-automatically in accordance with the principles of the present invention.

20 In these drawings:—

Figure 1 is a side elevational view of one form of machine or rapid fire gun constructed in accordance with the principles of the present invention;

25 Figure 2 is a longitudinal sectional view of the body or receiver of the gun and parts carried by or working within the same, the operating parts being shown in substantially the rearmost positions to which they are moved by the shock-operated means;

30 Figure 3 is a detail view of the body or receiver, with the parts in position ready to move into firing position when the trigger mechanism is actuated;

35 Figure 4 is a similar view but showing the operating parts in the positions they occupy at the instant of firing;

40 Figure 5 is a longitudinal sectional view of the forward portion of the gun showing one form of means for producing the shocks or rapid pressure impulses, and means for transmitting the shocks or impulse to the actuating mechanism of the gun, the latter means being shown in position corresponding to that of the parts in Figure 4;

45 Figure 6 is a cross-sectional view through the butt-tang, looking toward the muzzle of the gun and showing the rear sight;

50 Figure 7 is a view of the butt-tang looking toward the rear;

Figure 8 is a sectional detail plan view of the butt-tang and rear sight;

55 Figure 9 is an end view of the body or receiver, looking toward the muzzle of the gun, with the butt-tang removed;

60 Figures 10, 11, 12, 13, 14, 15, 16, and 17 are cross-sectional views of the gun, taken respectively on the lines 10—10, 11—11, 12—12, 13—13 and 14—14 of Figure 2, and the lines 15—15, 16—16 and 17—17 of Figure 5;

65 Figure 18 is a detail side elevational view of part of the body and trigger mechanism, looking at the side of the gun opposite to that shown in Figures 2, 3 and 4;

Figure 19 is a plan view of the trigger mechanism, removed from the body of the gun;

70 Figure 20 is an underneath plan view of the rear part of the trigger mechanism;

Figure 21 is an end view of the trigger mechanism looking toward the rear thereof;

75 Figures 22 and 23 are detail sectional views of the trigger mechanism, showing the operative parts thereof respectively in the "safety" and "automatic" positions, and

Figure 24 is a view similar to Figure 23, but showing the parts in their relative positions when the trigger is pressed;

80 Figures 25 and 26 are detail plan views, partly in section, of the trigger mechanism, the operative parts being shown respectively in the positions corresponding with Figures 22 and 23;

Figure 27 is a detail plan view of the 85 breech block or bolt;

Figure 28 is an elevational view of the forward end of the bolt;

Figure 29 is a sectional view taken on the line 29—29 of Figure 27, and showing the 90 extractor member carried by the bolt;

Figure 30 is a longitudinal sectional view of the body of the gun taken approximately on the line 30—30 of Figure 12, and showing the ejector mechanism in the act of 95 ejecting an empty shell;

Figure 31 is an outside elevational view of the cartridge magazine;

Figure 32 is a plan view of said magazine;

Figure 33 is a sectional plan view of the 100 magazine showing the arrangement of the cartridges therein; and

Figure 34 is a detail perspective view of the spring-actuated follower of the magazine.

105 In one form the means for utilizing the gases of discharge to produce the shock comprise a chamber and a piston member movable within the said chamber, the movement of the piston member being transmitted to the actuating mechanism of the firearm. The said chamber is formed between the gun barrel and a casing surrounding the latter along its entire length and extending forward in front of the muzzle end thereof.

110 At its forward end the wall of the casing is turned inwards forming an inwardly projecting flange having a central aperture or mouth of slightly greater diameter than that of the bullet. This arrangement permits the 115 free passage of the bullet. When the rear end of the bullet has left the muzzle end of the gun barrel and during the small fraction of a second the bullet takes to pass

120 through the aperture in the end of the casing, the discharge gases expand within the chamber transmitting a wave of high pressure through the air within the chamber, thereby driving the piston member backwards and operating the actuating mecha-

nism of the gun. When the rear end of the bullet has left the mouth of the casing the confined gases in the chamber and inside the gun barrel can issue freely through the 5 mouth of the casing. The gases still at high pressure within the gun barrel issue from the muzzle thereof and expand with great turbulence within the chamber simultaneously with the escape of gases through the 10 mouth of the casing. During the initial part of this period the pressure wave transmitted rearwardly inside the chamber to the piston member is increasing in intensity and finally reaches a maximum. The maximum 15 pressure on the piston is succeeded by a fall of pressure, the gases issuing from the mouth of the casing with sufficient kinetic energy to induce a partial vacuum within the chamber and gun barrel. Meantime the piston member 20 is still moving rearwards and may be made to uncover a passage formed by an enlargement of the diameter of the wall of the casing. A free passage is then provided inside the casing from the rear end thereof 25 to its mouth. Fresh cold air enters the chamber through inlet ports near the rear end of the casing, and a powerful draught is induced by the kinetic energy of the gases still issuing from the mouth of the casing.

30 The pressure and kinetic energy transmitted to the piston member is employed partly in effecting the backward stroke of the actuating mechanism and partly in energizing a "return spring" which is caused to 35 effect the forward or return stroke of the actuating mechanism.

It is to be particularly observed that the 40 velocity of the gases issuing from the mouth of the casing is that due to the head or pressure within that portion of the chamber between the muzzle end of the barrel and the mouth of the casing. This pressure varies rapidly but its maximum and average values are much less than the corresponding values 45 in the case of discharge gases issuing from the muzzle of a gun of ordinary construction. In the latter the maximum velocity of efflux of the discharge gases is of the order 10,000 feet per second; with the expansion in the 50 chamber provided by the present invention, the maximum velocity of efflux of the discharge gases is considerably less. Accordingly, the velocity and momentum of the 55 discharge gases and therefore also the momentum of recoil of the gun, are all greatly reduced by the present invention, and also the rapidly moving discharge gases as they impinge upon the shock producing obstruction in their path partially neutralize and 60 materially lessen the free recoil of the arm.

Referring more in detail to the drawings, and particularly to Figures 2, 3, 4 and 5 thereof, it will be noted that the gun barrel 1 at its rear or breech end has a screw- 65 threaded connection at 2 with the forward or

breech end of the body or receiver 3. Surrounding the barrel 1 throughout its entire length is a casing 4 which at its rear end is mounted upon the forward end of the body 3, being shaped to properly fit upon said 70 forward end as will appear from Figure 14, and being securely connected thereto by any suitable means. The particular means shown comprises a band 5 which is split at its lower part, as shown clearly in Figures 2 75 and 13, and has its two ends provided with screw-threads 6 and conical surfaces 7, which are arranged to co-act with similar screw-threads and conical surfaces on the interior of a nut 8, the exterior surface of which may 80 be knurled or roughened in any suitable manner. The edges of the band 5 are inwardly flanged at 9 to co-act with the outwardly projecting flanges 10 formed on the forward end of the body 3, and the rear end 85 of the casing 4, so that by applying the band over the ends of the body and casing and tightening the nut 8 on the threads 6, the halves of the band are caused to tightly grip the body and casing, and the flanged 90 edges 9 co-act with the flanges 10 to securely hold the casing on the body, with its rear surface abutting against a shoulder on the latter, as clearly shown in Figures 2 and 4.

95 The forward portion of the casing 4 is supported by means of a spider support 11, Figures 5 and 17, consisting of a cylindrical sleeve fitting onto the cylindrical portion 12 at the muzzle end of the barrel 1, 100 and provided with radially extending arms or fins 13 which engage at their outer edges with the interior of the casing 4. To afford additional support to the casing, some or all of the arms 13 may extend rearwardly beyond the rear end of the sleeve 11, with their outer edges engaging the interior of 105 the casing, as shown in Figure 5.

The forward portion 14 of the casing 4 is reduced in size, so that it is concentric 110 with the gun barrel 1, the casing being of larger diameter than the barrel so that an annular space 15 is formed between them, which will be referred to later. The portion 115 of the casing 4 to the rear of the shoulder 16 is of the cross-section illustrated in Figures 14 and 15.

The extreme forward end 17 of the casing 120 extends some distance beyond the forward or muzzle end of the gun, as shown in Figure 5, and constitutes one form of means for producing the shocks or pressure impulses which are utilized to effect operation of the actuating mechanism of the firearm. This forward end 17 may be formed in 125 various ways in order to produce the shocks or pressure impulses. Thus, as illustrated in Figure 5, the casing wall at its forward end is turned inwardly as shown at 18 to produce an inwardly extending flange forming in 130

effect an apertured forward wall on the casing, which permits the passage of the bullet and the subsequent retarded escape of the gases of discharge. As the gases of discharge flowing freely from the muzzle end of the barrel, following the discharge of the bullet therefrom, come into contact with the apertured forward wall 18 of the said casing or chamber, the consequent momentary check or retardation of the gases causes the production of the aforesaid shock or backward pressure impulse, and this shock or impulse may be transmitted backwardly to the actuating mechanism by suitable means, as hereinafter referred to. By regulating the size of the aperture in the forward wall 18 of the casing 4, or the distance of said wall from the muzzle end of the gun barrel 1, or by suitably proportioning the size of the aperture and the distance between the wall and muzzle end of the gun barrel, a pressure impulse or shock may be produced of such energy as to effect operation of the actuating mechanism in the most satisfactory and efficient manner. The regulation of the size of the aperture and its distance from the end of the barrel permits the energy of the shock or impulse to be determined with extreme accuracy, whereby the actuating mechanism may be operated with great nicety and smoothness and without imparting unnecessary shocks to the same or otherwise straining the parts of the gun.

The forward portion 17 of the casing 4 terminating in the apertured end wall 18, may be of cylindrical form, so that the shock or impulse is produced entirely by the contact of the rapidly moving gases with the said apertured wall, or as shown in Figure 5, said portion may be of slightly conical or tapered form, the conical or tapering wall of said portion co-operating with the apertured end wall in producing the shock or impulse.

Alternatively the checking or retarding of the gases of discharge may be effected entirely by tapering the wall of the forward portion of the casing 4, the extreme forward end of the casing being open, and the forward movement of the gases being checked or retarded due to the passage of said gases through the chamber of gradually reducing cross-section formed by the tapering wall of the casing. It will be clear that in this case also, by regulating the size of the aperture at the forward end of the casing or by regulating the distance of said aperture from the muzzle end of the barrel, or by suitably proportioning the size of the aperture and the distance of the same from said muzzle, the energy of the shock or impulse produced may be accurately controlled. Further, the checking or retarding of the gases might be effected by the use of a forward casing portion of cylindrical form having its extreme

forward end open by so determining the internal diameter of said portion that the free expansion of the gases of discharge from the muzzle end of the gun barrel into the chamber formed by said casing portion is momentarily checked as the bullet is discharged. 70

The shocks or impulses produced by the regulation of the discharge gases in the manner above described, or in any other suitable manner, may be transmitted to the actuating mechanism of the firearm by any suitable means. For example, they may be transmitted through the medium of a piston working in a suitable cylinder and connected by a rod or other convenient means to the bolt or other part of the actuating mechanism. In the particular construction illustrated in Figure 5, a piston 19 of annular form is arranged to reciprocate within the annular space 15 between the casing portion 14 and the gun barrel. The forward end or head of the piston 19 is bored to fit upon a cylindrical portion 20 of the gun barrel, and at its outer periphery said head fits the interior surface of the concentric portion 14 of the casing. 90 The head of the piston may be grooved as at 21 to prevent leakage, or may be otherwise packed. At its rear end the piston 19 is provided with a radial extension 22, Figures 5 and 15, to which is connected, as by means of screw-threads, although it may be integral therewith, if desired, the forward end of a piston or connecting rod 23. This rod extends rearwardly into the body or receiver 3 and is therein connected to an operating member 24, hereinafter referred to. The radial extension 22 and rod 23 are arranged to reciprocate within the enlarged portion of the casing 4 to the rear of the shoulder 16, the rod being guided in the forward end of the body 3, and preferably being of tubular form to reduce the weight while retaining the necessary strength. 105

It will be noticed that the annular space 15 in front of the piston 19 is in free communication with the chamber formed by the forward end 17 of the casing 4, so that a column of air is always maintained in front of the piston. On the firing of a cartridge or powder charge, the sudden shock or rapid pressure impulse produced by the retarding or checking of the discharge gases in the manner above described, is transmitted to the column of air in front of the piston 19 and by said column to the piston itself, the latter being thereby moved rearwardly so as to actuate the operating member 24. The spider support 11 as will be seen from Figure 17, permits the free communication between the space 15 and the chamber within the casing portion 17, while affording the necessary support for the casing. 115 120 125

The actuating mechanism of the firearm is located within the body or receiver 3, and the particular arrangement of such mechanism 130

illustrated, but to the use of which the invention is not in any way restricted, comprises essentially the cylindrical operating member 24 to which the rod 23 is connected, 5 the hollow cylindrical breech block or bolt 25, and the firing pin 26 slidably arranged within said block or bolt, as will be clear from Figures 2, 3, 4, 9 and 10. The body 3 of the gun is formed with two longitudinal 10 parallel bores 27 and 28, Figures 2 and 9 to 12, which are connected throughout practically their entire length by the slot 29. The operating member 24 is guided in the upper bore 27 and the breech block or bolt 25 is 15 guided in the lower bore 28. The operating member is provided with a post 30 which extends downwardly through the slot 29 of the body into the cam slot 31 formed in the upper surface of the bolt 25, said post having 20 a reduced portion which enters a slot in the firing pin 26, as will be clear from Figures 2 and 10. The return spring 32 surrounds a rearward extension on the operating member 24, bearing against said member 25 at its forward end, and at its rear end against the plate 33 of the butt-tang 34.

The cam slot 31 of the bolt 25, see Figure 27, comprises rear and forward portions connected by inclined cam surfaces 35 and 36, 30 with which the post 30 is adapted to engage during the forward and return movements of the operating member 24. The bolt 25 is provided at its upper part with a projection 37 which normally extends into the slot 29 35 and thereby prevents rotation of the bolt, but which when the bolt is in its extreme forward position coacts with a short circumferential slot 38 in the wall of the lower bore 28, indicated in dotted lines in Figure 40 12, and permits the bolt to be rotated, first in one direction and then in the other, by the engagement of the post 30 with the cam surfaces 35 and 36. The forward end 39 of the bolt is reduced in diameter and is provided with four angularly spaced locking or 45 resistance lugs 40 which are adapted to contact with four angularly spaced locking lugs 41 extending inwardly from the wall of the lower bore 28 at the forward end thereof, as 50 clearly shown in Figures 2 and 12. The firing pin 26 in the form illustrated is double ended, that is, it is provided with two oppositely extending firing projections 42, so that in the event of breakage of one projection, 55 the firing pin may be simply reversed to bring the other projection into operative position. Obviously, however, a single firing pin may be employed, or the post 30 might be provided or formed with a firing projection. 60 The firing pin 26 is slidably mounted within the bore of the bolt 25, the forward wall of the bolt being bored to substantially correspond with the firing projection 42, so that the extreme forward end of the latter will 65 when the pin is in firing position extend be-

yond the forward face of the bolt, to fire the cartridge, in the usual manner.

When the parts of the actuating mechanism are in the positions illustrated in Figure 3, and the bolt 25 is released, as herein-after described, the return spring 32 moves the operating member 24 forwardly, and the post 30 being in engagement with the inclined surface 35 of the cam slot 31, the bolt 25 moves forwardly with the post and 70 operating member, since said bolt is prevented from rotating by the projection 37 engaging the slot 29 in the body. As the parts advance in this relationship, the lower-most lug 40 engages the head of a positioned 75 cartridge 43 and forces the same in advance of the bolt into the chambered end of the gun barrel 1, the locking lugs 40 on the bolt passing freely between the locking lugs 41 on the body 3. When the movement of the 80 bolt is stopped by the engagement of the forward end thereof with the rear or breech end of the barrel 1, as shown in Figure 4, the projection 37 coincides with the circumferential slot 38 in the body, and as the 85 operating member 24 continues to advance, the post 30 due to its engagement with the inclined surface 35, rotates the bolt, through approximately one-eighth of a revolution, in order to bring the locking lugs 40 in front of 90 the lugs 41 on the body, to prevent rearward movement of the bolt when the cartridge is fired, the projection 37 moving within the slot 38. The operating member 95 24 after such rotation moves into the position 100 shown in Figure 4, the post 30 advancing within the forward portion of the cam slot, and moving the firing pin 26 into position to strike the head of the cartridge and fire the same. The bolt 25, it will be noted, is 105 securely locked against rearward movement before the firing pin can advance to fire the cartridge, so that the danger of premature explosion is entirely avoided. The operating member 24, during the described movement 110 thereof, through the medium of the rod 23 connected thereto, moves the piston 19 into its forward position, as indicated in Figure 5.

The discharge gases, following the bullet 115 thus discharged, issue from the muzzle end of the gun into the forward portion of casing 4, and the shock or rapid pressure impulse produced in the manner previously referred to is transmitted through the intervening 120 column of air to the piston 19 and causes the latter to move rearwardly on the portion 20 of the barrel, the rod 23 during such movement forcing the operating member 24 rearwardly. Said member on its initial rearward movement withdraws the firing pin 26, and the post 30 then engages the inclined 125 surface 36 of the cam slot 31, and rotates the bolt 25 in the reverse direction to that of its previous rotation, to bring the lugs 40 into 130

register with the spaces between the lugs 41 and the projection 37 into register with the slot 29. The post 30 then occupies the rear portion of the cam slot 31, as in Figures 5 2 and 27, and the bolt 25 is moved by the operating member 24 into its rearmost position, against the action of the return spring 32, which is compressed in order that it may effect a succeeding forward movement of the 10 parts. The rearward movement of the parts may be limited by the engagement of the rear of the extension on the operating member with the butt-tang plate 33, such movement being sufficient to ensure that the bolt 15 may be latched in its rear position. The shock or rapid pressure impulse produced by utilizing the gases of discharge in the manner described is thus transmitted to the actuating mechanism of the firearm to energize 20 said mechanism for a succeeding operation thereof.

The said actuating mechanism, after operation thereof by the aforesaid shock or pressure impulse, may be restrained from 25 further operation until manipulated by the user or operator of the firearm, in which event said actuating mechanism will be manipulable to cause the firing of individual rounds and will be re-energized by the shock 30 or impulse produced at each explosion of a cartridge. Or said actuating mechanism may be of such a nature, or so manipulable, that it is not restrained after each discharge of a bullet, in which event any desired number 35 of cartridges, or the full number of cartridges in the magazine may be successively exploded. With this arrangement the shock or pressure impulse produced by the novel utilization of the gases of discharge 40 of the first cartridge or shell exploded is caused, in the manner described, to energize the actuating mechanism of the firearm so that it will immediately operate to fire the succeeding cartridge or shell operatively positioned with respect to said mechanism, the gases of discharge produced at each explosion of a cartridge or shell thereafter 45 energizing the actuating mechanism to fire the succeeding cartridge or shell until the 50 desired number has been fired, or the magazine emptied.

These results may be accomplished by the use of the trigger mechanism illustrated in Figures 2, 3, 4, 9 to 11, and 18 to 26 of 55 the drawings, although other forms of trigger mechanism may be advantageously employed and the invention is not restricted to the use of that now to be described. This mechanism comprises a guard or support 60 44 slidably fitted to the lower part of the body 3, the side faces of the guard being provided with longitudinal slots 45, Figures 9 to 11, 21 and 23, adapted to co-act with longitudinal ribs or tongues 46 on the in- 65 terior of the lower part of the body, so that

the guard may be slid into place from the rear end of the body, the forward end of the guard abutting against a dividing wall 47 on the body, and the rear end of the guard being flush with the rear end of the body. 70

The guard 44 is provided at its upper portion with a recess 48, within which are located the sear 49 and the trigger 50 co-acting therewith. The sear is pivotally mounted on a pin 51, and is normally held 75 by a spring 52 with its forward end against a stop 53 extending across said recess and its rear end elevated and extending through a slot 54 in the body 3, into the lower bore 28 of said body. The sear is thus normally 80 in a position to engage a notch 55 in the bolt 25, when the latter is moved rearwardly a sufficient distance, in the manner described, in order to restrain said bolt against the pressure of the return spring. The trigger 85 50 is pivotally mounted on a pin 56, herein-after more fully referred to, and is normally held by a spring 57 with its rear end in contact with the stop 53. The rear end of the trigger is bifurcated at 58, as shown 90 particularly in Figures 19, 25 and 26, to receive the forward reduced end of the sear 49, and to provide a shoulder 59 adapted to co-act with said end of the sear.

In Figures 2, 3, 4 and 19, the sear 49 95 and trigger 50 are shown in the relative positions which they occupy when the gun is to be fired semi-automatically, that is when an individual round is to be fired at each pressure of the trigger. With the 100 parts in these relative positions, it will be noticed that when the trigger 50 is pressed its bifurcated rear portion will move upwardly in the recess 48, and the shoulder 59 will engage underneath the reduced forward end of the sear 49 and will raise said end, lowering the rear end of the sear from the notch 55 in the bolt and thereby releasing the latter and permitting it to be advanced by the return spring 32 acting 105 through the operating member 24 and post 30 in the manner already described. When the bolt is thus released and moves forward, the shoulder 59 snaps past the forward end 110 of the sear, as shown in Figure 4, due to the 115 relative movements of the trigger and sear about their respective pivot pins, and the sear is returned to its initial position ready to engage and hold the bolt when the latter is returned to its rear position by the shock 120 or pressure impulse produced following the discharge of the bullet. Figure 2 shows the parts in substantially the rearmost positions to which they are moved, the sear 49 having just engaged the notch 55 in the bolt, and Figure 3 shows the parts "ready to fire" the operating member having been advanced slightly relatively to the bolt to engage the post 30 with the inclined surface 35. The trigger 50, when relieved of the pressure 125 130

thereon, is returned to its initial position by its spring 57, the elongated aperture 60 permitting the necessary slight forward movement of the trigger to enable the shoulder 59 to pass by the forward end of the sear in resuming its normal position.

The trigger and sear are, however, adapted to occupy relative positions other than those shown in Figures 2, 3 and 4, that is, they may occupy the "safety" positions indicated in Figures 22 and 25, in which the trigger may be pressed without actuating the sear, or they may occupy the "automatic" positions indicated in Figures 23, 24 and 26, in which while the trigger is held pressed, the sear is retained in inoperative position.

By referring to Figures 11, 19, 25 and 26, it will be seen that the trigger 50 is pivotally mounted upon the eccentric central portion 61 of the pivot pin 56, this eccentric portion lying within the elongated aperture 60 of the trigger. The pin is provided with an enlarged screw-threaded portion 62 threaded into an aperture in the guard 44 to retain the pin in place, and with a handle 63 by means of which the pin may be rotated.

When the pin is rotated by means of the handle 63 in a counter-clockwise direction through approximately a quarter revolution, from the position shown in Figures 2, 3 and 19 to that shown in Figures 22 and 25, the trigger is moved slightly forwardly by the eccentric portion 61, so that the shoulder 59 is advanced to bring it just in front of the forward end of the sear and when the trigger is pressed the shoulder will rise in front of the forward end of the sear without actuating the latter. Thus pressure on the trigger while in this "safety" position, merely rocks the trigger on its pivot pin and the sear is not actuated, neither is the bolt released. When the trigger is in this position the gun may be carried in entire safety with the bolt held in the position shown in Figures 2 and 3 and without danger of the firearm being discharged by accidental pressure upon the trigger.

When the pin 56 is rotated by the handle 63 in a clockwise direction through approximately a quarter of a revolution, from the position shown in Figures 2, 3 and 19 to that shown in Figures 23, 24 and 26, the eccentric portion 61 of the pin moves rearwardly and permits a slight rearward movement of the trigger so that the shoulder 59 passes farther beneath the front end of the sear, as in Figure 23. Thus when the trigger is pressed, the shoulder 59 engages the front end of the sear and actuates the same to release the bolt as previously described, but instead of snapping past the end of the sear, as indicated in Figure 4, said shoulder remains in engagement therewith so long as the pressure on the trigger is maintained,

and holds the rear end of the sear in depressed inoperative position, as indicated in Figure 24. The bolt then on its rearward movement is not held by the sear, but when it has moved rearwardly sufficient to clear 70 the head of the succeeding cartridge 43, it is again pressed forwardly by the spring 32, the operation being repeated until the trigger is released, or the magazine exhausted.

There is thus provided a shock-operated 75 automatic firearm the actuating mechanism of which may be manipulated to fire individual cartridges, or to fire entirely by shock-operation, after the discharge of the first cartridge, any desired number thereof 80 within the capacity of the magazine.

The handle 63 is somewhat resilient or springy and is provided with a notch or groove 64 adapted to co-act with the part 65 of the guard 44 to normally hold the trigger 85 50 in the "semi-automatic" position, as in Figure 2. When the handle is moved into the "safety" or "automatic" positions indicated in dotted lines in Figures 25 and 26, it is held in such positions by its resilient frictional pressure against the exterior surface 90 of the guard 44. It is, of course, understood that the pin 56 is so constructed that the slight axial movements thereof when it is rotated, due to the screw-threads on the portion 62, will not interfere with the movements 95 of the trigger or cause the parts to jam, sufficient play being allowed to permit these movements.

It will be noted that the rod 23 is connected to the operating member 24 by means of a charging handle 64^a, the flat portion of which passes through slots in the member and rod and works in a longitudinal slot 65^a in the body 3. By manual rearward operation of this handle 64, the operating member 24, bolt 25 and piston 19 may be moved into the positions shown in Figure 3 ready to fire a cartridge. The flat portion of the handle is provided with ridges 66, preventing withdrawal of the handle excepting through the enlarged rear portion 67 of the slot.

The cartridges 43 may be fed into the chambered end of the barrel 1 from a magazine of any convenient or usual type, but preferably these cartridges are arranged within a magazine 68, illustrated particularly in Figures 2, 4, 12 and 31 to 34. This magazine consists of a casing the side walls 115 of which are substantially parallel and arranged at such a distance apart that the cartridges 43 placed therein form a double row with the cartridges in staggered contacting relation as indicated in Figures 12, 125 32 and 33. The lowermost cartridges rest upon a platform or follower 69 which is pressed upwardly by means of the spring 70 of usual form. The platform 69 (see Figures 12 and 34) has a portion thereof 130

pressed upwardly at 71 to support one of the lowermost cartridges in its staggered relation to the other thereof, and to enable the upward pressure of the spring to be positively and directly imparted to both rows of cartridges, so that the group of cartridges is moved upwardly as a unit, and jamming of said cartridges in the magazine is prevented. The side walls of the magazine are preferably formed with inwardly projecting ribs 72 with which the cartridges engage, as shown in Figure 33, these ribs reducing the extent of contact of the cartridges with the magazine walls and facilitating the upward movement of the cartridges under the action of the spring. The side edges of the platform or follower 69 may engage these ribs, or they may be notched to receive the ribs which then serve to guide the follower in its upward and downward movements.

The side walls of the magazine at the upper ends thereof are inclined or converge toward each other as indicated at 73, and the extremities of these walls are curved as indicated at 74, to enable them to contact with and fit partially around the surface of a single cartridge 43. The centre of curvature of the extremities 74 lies in the longitudinal median plane of the magazine. Thus when the uppermost cartridge 43, Figure 12, is removed from the magazine by the bolt 25, the next lower cartridge 43' is pressed upwardly into contact with the inclined or converging end 73 of the side wall of the magazine and is guided by said inclined end toward the longitudinal median plane of the magazine, and is finally pressed by the cartridge 43² beneath it into contact with the curved extremities 74 of the side walls, being positioned by said walls for engagement and removal by the bolt. When the cartridge 43' so positioned is removed by the bolt, the cartridge 43² is similarly pressed upwardly and guided by the inclined or converging end of the opposite side wall of the magazine into position between the extremities 74, the operation being repeated at each removal of a cartridge. Thus cartridges are positioned for engagement by the bolt, alternately from the two rows of cartridges in the magazine, and it will be noticed that each cartridge engaged by the bolt occupies identically the same position as its predecessor occupied, and follows the same path as its predecessor when forced by the bolt into the chambered end of the barrel, this path lying at all times in the vertical longitudinal median plane of the gun. Thus absolute uniformity in the feeding of the cartridges to the gun barrel is obtained with a double-row magazine, or in other words, the advantageous uniform feeding action obtained with a single-row magazine is obtained with the use of a double-row

magazine, instead of the alternate feeding first from one side and then from the other obtained with the usual double-row magazines. This uniformity in the feeding of the cartridges necessarily increases the efficiency of the gun in operation.

The cartridges might be guided into place between the extremities 74 by pressing the metal of the side walls inwardly a greater distance at the upper ends of the ribs 72, to form inclined or converging ribs, from a point below the inclined ends 73 to said extremities 74, these converging ribs then guiding the cartridges into place. These inclined or converging ribs might be used with a magazine having plain side walls, or the upper end of the magazine might be otherwise formed to ensure the cartridges being guided alternately from the two rows thereof into the longitudinal median plane of the magazine.

The forward portions of the side walls of the magazine converge toward each other, as indicated in Figure 33, following substantially the curvature of the bullets 75, the platform or follower 69 being correspondingly shaped at its forward end.

It will be noted from Figures 2, 31 and 32, that the curved extremities 74 of the side walls of the magazine extend substantially half-way from rear to front of the magazine and their extreme forward edges co-act with each cartridge during its movement by the bolt, to hold its rear end or head in the magazine until the bullet 75 is guided by the inclined surface 76 on the body, into the chambered end of the barrel. The cartridge is then released from said extremities, and by the movement of the succeeding cartridge into place, is thrown upwardly slightly to bring it into substantial alignment with the axis of the barrel.

The spring 70 is preferably secured to the follower 69 by means of lugs or ears 77 bent over at the side edges of the follower, and between which lugs and the follower the upper leaf of the spring is inserted. These lugs may be formed on the follower by rolling or pressing down the forward side edges thereof, so as to shape the forward end of the follower and at the same time form the lugs, between which and the follower the forward end of the upper leaf of the spring is inserted. The spring may be similarly secured to the bottom plate 78 although it may of course be secured to the follower, or to the bottom plate, in any other convenient way.

The bottom plate 78 may be soldered or otherwise permanently secured to the walls of the magazine, or said plate may be removably secured thereto by suitable catches on said plate or said walls, which are releasable by an operator equipped with a suitable tool, to permit the follower and

spring to be removed and replaced when desired.

The front and rear walls of the magazine are preferably slightly curved as indicated in Figures 2, 4 and 31, to allow for the curvature or inclination of the front and rear ends of the group of cartridges due to the slight tapering of the walls thereof. The upper edge of the rear wall is curved coincidentally with the wall of the bore 28, and the extremities 74 hold the cartridges so that the heads thereof project just sufficiently above said curved edge to enable them to be engaged by the bolt. The cartridges are inserted in the magazine through the opening in the top thereof in the usual manner, and the magazine may be constructed to hold five, ten, fifteen, twenty or other suitable number as may be desired.

20 The magazine is inserted in a recess formed in the lower part of the body, in communication with the lower bore 28 therein, the forward wall of the magazine having an aperture adapted to engage over a pin 79 in the forward wall of the recess, and the rear wall co-acting with a latch 80 which extends through an aperture in the wall 47 into a notch or aperture 81 in the said rear wall, which wall may be slightly pressed out above the notch, as indicated to more securely co-act with the latch.

The latch 80, as shown in Figures 2, 19 and 20, is mounted in a recess in the forward end of the guard 44 of the trigger mechanism, the latch having tongues 82 on its side faces co-acting with corresponding grooves in the walls of said recess, and being pressed forwardly by a spring 83. The forward and rearward movements of the latch are limited by a pin 84 co-acting with a groove or recess 85 in the upper face of the latch. By rearward pressure against the rear curved end 86 of the latch, which is located in close proximity to the trigger 50, the forward end of the latch may be released from the notch 81, thus permitting the magazine to fall or be removed from the recess in the body. Thus without substantially changing the position of the hand in firing, an empty cartridge magazine may be released from the firearm and a loaded magazine substituted in place thereof by means of the other hand, enabling the re-loading of the firearm to be effected with extreme rapidity and ease.

When a cartridge is pressed into the chambered end of the barrel, its rear end or head as indicated in Figure 4, extends into a recess 87, in the forward end of the bolt 25 and the extractors 88 which normally extend inwardly into said recess snap over the rim of the cartridge head in the usual way, so that the empty cartridge case is withdrawn from the end of the barrel when the bolt moves rearwardly. The improved con-

struction and arrangement of the extractors 88 is indicated in Figures 27 to 30, and it will be noted that they are formed from a single piece of resilient metal, comprising a curved body portion 89 from which the two extractors 88 extend longitudinally, and which has a pair of laterally extending arms 90. The reduced forward end 39 of the bolt at or adjacent the junction thereof with the main portion of the bolt is cut away to form the tapering or inclined walls 91. The extractor member is laterally applied to the bolt by pressing the resilient arms 90 over the spaced edges 92 of the walls 91, the arms 90 then moving together to grip said walls, as indicated in Figure 29, and securely holding the extractor member in place on the bolt. The extractors 88 and body portion 89 preferably lie in recesses in the forward end 39 of the bolt so as to be flush with the circumferential surface thereof. This construction provides an extremely neat, simple and easily manufactured extractor member and one which can be readily applied and removed when necessary.

During the rearward movement of the bolt, the empty cartridge case is ejected by the ejector mechanism illustrated in Figures 10, 12 and 30. The ejector member 93 is centrally pivoted within a chamber or recess 94 at one side of the body 3, this recess communicating with the bore 28 through apertures 95 and 96. The bolt 25 at its rear end is provided with a cam surface 97 which at a predetermined point in the return movement engages the rear end of the ejector member 93, which extends into the bore 28 through aperture 95, and presses the said end into the recess 94, forcing the forward end of said ejector member through aperture 96, into the bore 28 and into contact with the empty cartridge case held by the extractors 88. The cartridge case is thus ejected from the recess 87 in the end of the bolt through an ejection aperture or slot 98 formed in the wall of the body 3, Figures 2 and 12. The chamber or recess 94 is closed by means of a cover plate 99 sliding in grooves in the outer edges of the recess walls, one end of the cover, which may be the front end as in Figure 1, or the rear end as in Figures 4 and 10, having a lateral lug or ear 100 which extends into a recess 101 in the body, whereby the cover may be removed by inserting the end of a bullet in said recess to engage the lug 100 and sliding the cover forwardly or rearwardly in its guiding grooves.

It will be noted that the ejector member 93 is arranged in a plane which is inclined from the horizontal plane passing through the axis of the bore 28 of the body, whereby the amount of projection of the walls of the recess 94 from the body 3 is 130

reduced to a minimum, this adding to the neat appearance of the firearm, and reducing the danger of the gun being caught in or damaged by obstructions. The ejection 5 aperture 98 is arranged in a plane inclined to the said horizontal plane and beneath the same so that the empty cartridge cases are thrown outwardly and downwardly and do not interfere with the operator either in operating or sighting the gun.

The butt stock 102 may of course be secured to the butt tang 34 in any usual or convenient manner, but it is preferably secured thereto by the means illustrated in 15 Figures 1, 2, 6 and 8. That is, the stock is secured to the tang by means of a tube 103 which is screw threaded at its upper and lower ends. The upper end of the tube is threaded into the interiorly screw-threaded lugs 104 projecting rearwardly and downwardly from the butt tang plate 33. The butt stock is bored to fit over the tube 103 and its upper end is shaped to fit within and be flush with the exterior surface of 25 the rearwardly extending flange 105 of the butt tang. The butt-plate 106 is formed with a recessed portion 107 pressed outwardly therefrom, which fits within a recess in the rear end of the butt stock. The 30 rear end of the tube 103 extends into the recessed portion 107 and a nut 108 threaded onto the end of the tube and pressing against the wall of said portion securely holds the butt plate, stock and tang together. The 35 nut 108 may be provided with ears 109 to which are hingedly connected cover plates 110 adapted under the influence of a spring (not shown) to respectively cover the opening in the recessed portion 107 and the end 40 of a chamber 111 formed in the stock below the tube 103, said tube and chamber serving to receive cleaning rods, oil-can, and other accessories. The butt plate is also provided with ears 112 lying within a recess in the 45 stock and between which is pivotally connected the rear sling swivel 113, such swivel thus being securely connected to the butt plate instead of by screws to the butt stock as usual. The assembled butt stock and 50 tang are removably connected to the body 3 in the manner illustrated in Figures 2, 4, 7, 8 and 9. The tang is formed with a forwardly extending flange 114 the forward edge of which has an inwardly extending 55 flange 115, the flange 114 corresponding in shape to the rear end of the body, as will be seen from Figures 7 and 9, and its lower portion being open or cut away as shown in Figure 7. The rear end of the body 3 is 60 provided with an outwardly extending flange 116. The tang may thus be slid downwardly over the end of the body portion, with the said end in contact with the butt tang plate 33, and the flange 114 will 65 when the tang is in place, prevent down-

ward and lateral movement thereof, and the plate 33 and the co-acting flanges 115, 116 will prevent relative longitudinal movement between the tang and body. To prevent the tang being removed upwardly from the body 70 except when it is desired to disconnect the stock and tang from the body, the plate 33 is provided at its lower part with a notch or aperture 117 with which the nose 118 of a pivotal latch 119 is adapted to engage. 75 This latch is pivoted on a pin 120 within a recess 121 in the rear end of the guard 44 of the trigger mechanism, this latch when in the position indicated in Figure 4 permitting the butt tang to be applied and removed, and when in the position indicated in Figure 2 preventing removal of the tang by engagement of its nose 118 with the lower wall of the notch 117. The forward portion of the latch is bifurcated at 122, see Figures 80 19 and 20, and the arms of the bifurcation are normally slightly spread apart, so that when in the position of Figure 2, they resiliently engage the walls of the recess in the guard with sufficient pressure to hold the 85 latch in locking position. The forward end of the latch is provided with an aperture 123 and the guard adjacent said aperture has recesses 124, so that by insertion of the pointed end of a bullet in one of the recesses 90 and in the aperture 123 the latch may be readily released to permit the butt tang and stock to be removed from the body. 95

The firearm may be provided with rear and front sights constructed and arranged 100 on the arm in any usual manner known in the art. It is, however, preferred to arrange these sights in the manner shown in Figures 1, 2, 3, 5 and 6 to 8. From these figures it will be seen that the butt tang plate 33 is 105 provided with a vertical slot or recess 125 in which is slidably arranged the rear sight 126. The walls of the slot may be slightly undercut or dovetailed if desired and the edges of the sight correspondingly formed. 110 The head of the sight is formed with a peep or other sighting aperture or notch 127, and the body of the sight is bifurcated to provide two arms 128. These arms are slightly sprung away from each other, so that when 115 in place in the slot 125 the side edges of the sight are resiliently pressed into contact with the edges of the slot to hold or assist in holding the sight in any position to which it may be vertically adjusted within said slot. The edges of the sight and of the slot may be roughened, if desired, to assist in holding the sight in adjusted position. The sight is provided with suitable range graduations co-operating with zero marks 120 formed on projections 129 at the upper part of the tang. 125

It may in some or all cases, be desirable to provide other means for holding the sight 130 in its adjusted positions, and such means

may comprise the pin or bar 130 slidably mounted in bearings 131 in the butt tang transversely of the sight. This pin is provided with a recessed or cut-away portion 5 to enable it to fit over the sight as in Figures 2 and 8, and to provide a shoulder 132 adapted to co-act with one of the side edges of the sight. The pin is normally pressed outwardly by means of a spring 133 of 10 sufficient strength to hold the face of the shoulder 132 against the edge of the sight with sufficient pressure to prevent movement of the sight from its adjusted positions. The face of the shoulder 132 may be roughened if desired. The pin 130 is provided with a head 134, and it will be understood that by pressure of the thumb or other part against this head, the face of the shoulder may be moved away from the edge of the 15 sight to permit vertical adjustment of the latter in accordance with the range desired, as indicated by the range graduations co-operating with the zero marks, and that when the pressure on the head is relieved, 20 the spring will again force the face of the shoulder against the edge of the sight to hold the same firmly in its adjusted position. There is thus provided an extremely simple construction of rear sight which may be 25 quickly and easily adjusted to the desired range and which may be readily replaced in case of damage or breakage. In its innermost position, the upper part of the sight is practically flush with the upper part 30 of the tang and the danger of breakage of the sight or of catching the same in obstructions is reduced to a minimum.

The front sight 135 is mounted upon a split clip or band 136 which as will be clear from 40 Figures 5, 15 and 16, is shaped to fit the concentric and enlarged portions of the casing 4 and to abut against the shoulder 16 hereinbefore described. The clip is adapted to be passed rearwardly along the concentric 45 portion 14 of the casing 4 and to be firmly secured in place thereon against shoulder 16 by means of the screw 137 passing through an aperture in one of a pair of ears 138, depending from the lower portions of the 50 clip, and threaded into the other of said ears, Figure 16. The screw 137 also forms a pivot for the stacking swivel 139 located between said ears 138, and when tightened not only serves to clamp the halves of the 55 clip firmly against the surface of the casing, but also to grip the swivel 139 between the ears for a purpose later referred to. A second pair of ears 140 depend from the lower portions of the clip 136 and between these 60 is pivoted the front sling swivel 141 this swivel preferably being formed with pivots 142, Figure 15, held within the apertures in the ears by the resiliency of the clip and the tightening of the screw 137.

65 In light machine guns such as illustrated

in the drawings, it is usual to provide a firing mount or rest for the gun so that the same while being fired may be supported from the ground or other object if desired. It may also be desirable to provide a guard 70 or shield to protect the machine gunner from being struck by enemy bullets, shell splinters or the like. In Figures 5, 15 and 16, is illustrated a metallic member or plate 143 which may serve not only as a firing mount 75 or support for the gun by resting the lower part thereof against the ground or other object, but which also serves as a shield or protector for the head or body of the gunner when firing the gun. It will also be 80 clear that the mount or shield 143 serves as a body protector for the gunner when advancing with the gun held substantially horizontally in the usual manner, as the shield will thus be held in front of the gunner's body and will afford some measure of protection thereto. The shield is preferably of convex or dished form as illustrated in Figure 5 so that bullets on striking the same may glance obliquely from 85 the surface thereof.

The mount or shield is mounted upon the clip or band 136, having a central aperture 144 which fits the concentric portion 145 of said clip, and other apertures 146, 147 extending from the central aperture, of which the former is of such shape as to pass over the stacking swivel 139 and the latter is in the form of a slot adapted to co-operate with the projection 148 at the upper end of the 95 swivel. The mount or shield is positioned on the clip 136 by passing it along the casing 4, (with the aperture 146 beneath the casing so that it will pass over the swivel 139, when the latter is in the dotted line position indicated in Figure 5) until the mount abuts against the shoulder 149 on the clip and against the ears 140. The mount is then turned to bring the aperture 146 into the upper position indicated in the figures, and 100 the slot 147 into line with the stacking swivel, and the latter is then rotated into the position indicated in full lines in Figure 5, so that its projection 148 will extend 105 into the slot 147 and prevent movement of the shield. The gripping of the swivel 139 between the ears 138, as previously mentioned, holds the swivel with sufficient pressure to prevent accidental movement of the same to release the mount. The edges of 110 the slot 147, it will be noted, are positioned between the two pairs of ears 138 and 140, and the mount is thus held firmly in place on the clip. The aperture 146, as will be 115 seen from Figure 15, provides a field of vision surrounding the front sight 135, so that the gun may be properly sighted. The mount or shield 143 may, of course, be secured on the gun by other means than those 120 illustrated and described.

It is desirable to cover the rear enlarged portion of the casing 4 with a heat-insulating covering 150, which as illustrated in Figure 14, is shaped to fit the said portion 5 of the casing. This covering which may be of wood or other suitable material, is held in place between the band 5, securing the casing to the body, and the front sight band 136, as shown in Figures 1, 2 and 5.

10 It will be understood from the previous description that the guard 44 of the trigger mechanism is held in place by the tang 34 when the latter and the butt stock are positioned on the body, and that said guard is 15 provided at its rear and front ends with means for holding in place the tang and butt stock, and the cartridge magazines. The lowermost edges 151 of the body 3 preferably extend downwardly a sufficient distance 20 to cover the pins 51, 84 and 120, of the trigger mechanism, so as to conceal these pins and at the same time to prevent accidental displacement thereof, the pins being simply pressed into place and held thereby 25 at 152 to receive the end of the handle 63.

The front wall 18 of the casing 4 may be formed in the manner indicated in Figures 1 and 5, so as to provide a means by which 30 a bayonet may if desired be readily secured on the tapering forward end 17 of said casing.

It will be understood that the shock or impulse operated piston 19 in addition to 35 serving to operate the actuating mechanism of the firearm, is so arranged that during its reciprocating movements it has a pumping effect on the air within the casing 4, and by providing air inlets at suitable points in 40 said casing, and in the covering 150, when used, the piston when reciprocated will force the warm air from the casing and draw cooler air thereinto. Further, the piston 19 when at or near the rear end of its 45 stroke does not touch the wall of the casing at the enlarged portion 4^a. A clear passage for air is then provided inside the casing from the inlet ports 40^a to the mouth. The discharge gases issuing from the mouth 50 of the casing induce a powerful draught, thus effecting a circulation of air between the casing and the gun barrel and effectively cooling the latter. If desired, the rod 23 may loosely fit within the forward portion 55 of the body, so that the piston 19 may circulate cooling air over the actuating mechanism of the firearm and within the body 3, for the purpose of maintaining said parts and body, in addition to the barrel, in cool 60 condition during operation of the firearm. Or the gases of discharge may be otherwise utilized to produce said circulation of cooling air.

It will be readily understood that the

aforesaid retardation or checking of the 65 movement or expansion of the discharge gases produces shocks or pressure impulses which serve to reduce or neutralize the recoil of the firearm due to the explosion of the cartridge so that the firearm may be operated more easily and with greater accuracy. 70

As previously indicated the essential feature of the invention is a firearm operated automatically or semi-automatically by 75 means of shocks or pressure impulses produced by means influencing the gases of discharge resulting from the firing of a cartridge or powder charge, as distinct from a firearm operated by the application 80 of the pressure of the gases of discharge against a part connected to the actuation mechanism. The invention is not restricted to any particular form of means for producing these shocks or impulses, although 85 various means for this purpose have been described in order that the invention may be clearly understood. Furthermore, the invention is not restricted to any particular construction or size or calibre of firearm, 90 as although the principles of the invention may be particularly applicable to rifles or shoulder arms, and for convenience a firearm of this character has been described in detail, the invention is also applicable, as 95 will be clearly understood by those skilled in the art, to firearms of other types or construction and of smaller and larger size or calibre.

Having now particularly described and 100 ascertained the nature of my said invention and in what manner the same is to be performed, I declare that what I claim is:—

1. An automatic firearm, comprising in 105 combination, a body portion, a barrel carried thereby, actuating mechanism located within said body portion, means acting upon the discharge gases to produce a shock or very rapid pressure impulse, and means for transmitting the energy of said shock 110 or impulse to said actuating mechanism to energize the same.

2. An automatic firearm, comprising in 115 combination, a body portion, a barrel carried thereby, actuating mechanism located within said body portion, means extending in advance of the muzzle end of said barrel and acting upon the discharge gases to produce a shock or very rapid pressure impulse, and means for transmitting the energy of said shock or impulse to said actuating mechanism to energize the same.

3. An automatic firearm, comprising in 125 combination, a body portion, a barrel carried thereby, actuating mechanism located within said body portion, means located in advance of the muzzle end of said barrel and co-acting with the discharge gases to

- momentarily check the forward movement thereof to produce a shock or very rapid pressure impulse, and means for transmitting the energy of said shock or impulse to said actuating mechanism to energize the same.
4. An automatic firearm, comprising in combination, a body portion, a barrel carried thereby, actuating mechanism located within said body portion, means surrounding the muzzle end of said barrel and extending in advance thereof to momentarily check the free expansion of the discharge gases to produce a shock or very rapid pressure impulse, and means for transmitting the energy of said shock or impulse to said actuating mechanism to energize the same.
5. An automatic firearm, comprising in combination, a body portion, a barrel carried thereby, actuating mechanism located within said body portion, a casing having a portion extending in advance of the muzzle end of said barrel to form a chamber in communication with the atmosphere at its forward end, said portion being constructed to act upon the forwardly moving discharge gases to impose a shock or wave of compression upon the body of air within said casing, and means within the casing for transmitting the energy of said shock to said actuating mechanism to energize the same.
6. An automatic firearm, comprising in combination, a body portion, a barrel carried thereby, actuating mechanism located within said body portion, a casing having a portion extending in advance of the muzzle end of said barrel to form a chamber in communication with the atmosphere at its forward end, a piston slideable within said casing at a material distance to the rear of its forward portion, said portion being constructed to act upon the forwardly moving discharge gases to impose a shock or wave of compression upon the body of air in advance of said piston, and a connection between said piston and said actuating means for energizing the latter.
7. An automatic firearm, comprising in combination, a body portion, a barrel carried thereby, actuating mechanism located within said body portion, a casing surrounding said barrel and having a portion extending in advance of the muzzle end thereof to form a chamber in communication with the atmosphere at its forward end, an annular piston slideable upon said barrel and fitting within said casing and having its forward end at a material distance to the rear of the muzzle end of the barrel, said casing portion being constructed to act upon the forwardly moving gases to impose a shock or wave of compression upon the annular column of air in advance of said piston, and a connection between said piston and said actuating means for energizing the latter.
8. An automatic firearm, comprising in combination, a body portion, a barrel carried thereby, actuating mechanism located within said body portion, means located in the path of movement of the discharge gases apertured to permit the passage of a bullet and adapted during such passage to momentarily confine and check the forward movement of said gases to produce a shock or very rapid pressure impulse, and means for transmitting the energy of said shock to said actuating mechanism to energize the same.
9. An automatic firearm, comprising in combination, a body portion, a barrel carried thereby, actuating mechanism located within said body portion, and means concentrically disposed about the axis of the gun barrel in advance of the muzzle end thereof to momentarily and uniformly check and confine the discharge gases to produce a shock or rapid pressure impulse without causing lateral deflection of said gases, for the purposes set forth.
10. An automatic firearm, comprising in combination, a body portion, a barrel carried thereby, actuating mechanism located within said body portion, means confining a body of elastic fluid, means operative upon the discharge gases to impress a shock or wave of compression upon said body of fluid, and means for transmitting the energy of said impressed shock to the actuating mechanism to energize the same.
11. An automatic firearm, comprising in combination, a body portion, a barrel carried thereby, actuating mechanism located within said body portion, a casing carried by said body portion and surrounding said barrel, said casing having its forward portion concentric with the barrel and extending beyond the same and being enlarged at its rear portion, air inlets in said enlarged rear portion of the casing, means at the forward end of said casing operative upon the discharge gases to produce a shock of compression and rarefaction, and means positioned within the concentric portion of the casing to receive said shock and movable thereby into the enlarged portion of the casing to permit the forward flow of cooling air through said inlets.
12. An automatic firearm, comprising in combination, a body portion, a barrel carried thereby, actuating mechanism located within said body portion, a casing surrounding said barrel and confining a column of air, means at the forward end of said casing operative upon the discharge gases to impress a shock or wave of compression

- upon said body of fluid and a piston within said casing to receive the impressed shock and transmit the same to the actuating mechanism to energize the same.
- 5 13. An automatic firearm, comprising in combination, a body portion, a barrel carried thereby, actuating mechanism within said body portion, means immovably arranged at the muzzle end of said barrel and 10 acting on the discharge gases to produce a shock or compression wave, and movable means receiving said shock or wave and transmitting the same to said actuating mechanism to energize the same.
- 15 14. An automatic firearm, comprising in combination, a body portion, a barrel carried thereby, actuating mechanism within said body portion, means immovably arranged at the muzzle end of said barrel to momentarily 15 check the forward movement of the discharge gases to produce a shock or compression wave, and movable means receiving said shock or wave and transmitting the same to said actuating mechanism to energize the same.
- 20 15. An automatic firearm, comprising in combination, a body portion, a barrel carried thereby, actuating mechanism within said body portion, means immovably arranged at the muzzle end of said barrel to momentarily 20 check the expansion of the discharge gases to produce a shock or compression wave, and movable means receiving said shock or wave and transmitting the same to said actuating mechanism to energize the same.
- 25 16. An automatic firearm, comprising in combination, a body portion, a barrel carried thereby, actuating mechanism within said body portion, immovable means surrounding the muzzle end of said barrel and extending forwardly therefrom and acting on 25 the discharge gases to produce a shock or compression wave, and movable means receiving said shock or wave and transmitting the same to said actuating mechanism to energize the same.
- 30 17. An automatic firearm, comprising in combination, a body portion, a barrel carried thereby, actuating mechanism within said body portion, a casing surrounding said barrel and extending in advance of the muzzle end thereof and fixedly connected to said body portion, said casing having a forward 30 portion constructed to act on the discharge gases to produce a shock or compression wave, and movable means within said casing receiving said shock or wave and transmit-
- ting the same to the actuating mechanism to energize the same.
18. An automatic firearm, comprising in combination, a body portion, a barrel carried thereby, actuating mechanism within said body portion, a casing surrounding said barrel and extending in advance of the muzzle end thereof and fixedly connected to said body portion, said casing having a forward wall apertured to permit the passage of the bullet and acting on the discharge gases to produce a shock or compression wave, and movable means within said casing receiving said shock or wave and transmitting the same to the actuating mechanism to energize the same.
19. An automatic firearm, comprising in combination, a body portion, a barrel carried thereby, actuating means within said body portion, means immovably located in the path of the discharge gases apertured to permit the passage of a bullet and acting on the discharge gases to momentarily confine the same to produce a shock or compression wave, and movable means receiving said shock or wave and transmitting the same to said actuating mechanism to energize the same.
20. An automatic firearm, comprising in combination, a body portion, a barrel carried thereby, actuating mechanism within said body portion, a casing immovably surrounding said barrel throughout the length thereof and extending in advance of the muzzle end of the same, and movable means within said casing spaced from the muzzle end of the barrel to provide a column of air in advance of said means, said casing at the forward portion thereof being constructed to act on the discharge gases to impose a shock or compression wave upon said movable means through said column of air.
21. An automatic firearm, comprising in combination, a body portion, a barrel carried thereby, actuating mechanism within said body portion, a chamber immovably located in advance of the muzzle end of said barrel to receive the discharge gases issuing therefrom and co-operating with the discharged bullet to momentarily confine and enclose said discharge gases to produce a shock or compression wave, and movable means associated with said chamber to receive said shock or wave and transmit the same to the actuating mechanism to energize the same.

In testimony whereof I affix my signature.

ISAAC N. LEWIS.
